[57] CLAIM

The ornamental design for a combined decorative display and aromatic infusion device for satchets of potpourri or bath herbs, as shown and described.

DESCRIPTION

FIG. 1 is a front elevational view of the combined decorative display and aromatic infusion device for satchets of potpourri or bath herbs showing my new design;

FIG. 2 is a rear elevational view thereof;

FIG. 3 is a right view thereof;

FIG. 4 is a left view thereof;

FIG. 5 is a top plan view thereof;

FIG. 6 is a bottom plan view thereof; and,

FIG. 7 is an exploded view thereof.

The cross-hatching in FIG. 7 represents conventional fabric and is understood to extend throughout the areas represented.
